UNITED STATES PATENT OFFICE.

JOSEPH M. BARRETT, OF FOSTORIA, OHIO, ASSIGNOR TO THE "S-C" REGULATOR MANUFACTURING COMPANY, OF FOSTORIA, OHIO, A CORPORATION OF OHIO.

AUTOMATIC ALARM AND SHUT-OFF FOR STEAM BOILERS.

Application filed February 27, 1922. Serial No. 539,790.

This invention relates to attachments for steam boilers for automatically giving an alarm in case of the water falling to a dangerous level. It also comprehends means, 5 which may be employed when fluid fuel is used, for shutting off such fuel when such dangerous condition arises, thus maintaining the boiler in safe working condition.

In operating boilers, particularly in isolated locations, such as oil fields, wherein one operator is employed for maintaining a number of such boilers in condition, it sometimes happens that the boiler feed water apparatus is impaired and that the 15 boilers are burned out before the operator is apprised of the situation in time to prevent the boiler from being damaged. Considerable difficulty has been experienced in obtaining an alarm which is positive in its 20 operation, and which is adapted to be readily attached to existing boilers.

Accordingly one of the objects of my invention is the provision of means which is adapted to be readily attached to existing 25 boilers and employed for giving an effective alarm whenever low water occurs. In addition, my invention contemplates the inclusion of a warning signal to an operator who may be at a point remote from the boiler, together with suitable mechanism (employed 30 if desired) for indicating at a separate control station the particular boiler requiring attention. I so arranged the alarms that once placed in operation they are caused to 35 remain in action, until an operator arrives at the boiler and manually releases the alarm actuating mechanism.

When my alarm is employed with a boiler having oil or gas fuel, I combine it with a 40 valve arranged to shut off the fuel by the same operation which actuates the alarm.

The means for accomplishing the above objects will be more fully set forth in the following description which relates to the 45 drawings, and the essential characteristics of my invention will be summarized in the claims.

Fig. 1 is an end elevation of a boiler showing portions of a control mechanism 50 embodying my invention; Fig. 2 is a side elevation of a portion of the boiler showing a valve control means actuated by the mechanism illustrated in Fig. 1; Fig. 3 is an elevation of a diaphragm operated valve 55 showing signal actuating mechanism with the

fuel valve in open position; Fig. 4 is an elevation of the mechanism shown in Fig. 3 with the valve stem in closed position; Figs. 5 and 6 are sections taken on the lines of 5—5 and 6—6 respectively in Fig. 3.

In the various figures, 10 indicates a boiler having a feed water line 11 and fuel line 12 adjacent the bottom thereof, and having connections 13 and 14 respectively above and below the normal water line. Intermediate the connections 13 and 14 I have shown a pressure control generator 15 which communicates through a tubular passageway 16 with a spring operated diaphragm valve 17 in the feed-water line. The generator 15 is mounted on a conduit 18 which may be formed of several lengths of pipe fitted together and secured to the connections 13 and 14, thus forming a closed circuit or by-pass, the lower portion of which is filled with water, and the upper portion with steam. A suitable blow-off conduit 20 having a valve 19 therein may be connected with the conduit 14.

The generator 15 comprises a secondary pressure chamber which depends for its operation on the difference in temperature between the steam and water within the conduit 18, and which is set to control the valve 17, thus insuring a steady flow of water to the boiler. I have shown my invention as embodying a generator 21 which is similar in construction to the generator 15, and which is adapted to communicate with one end of the conduit 22. The other end of such conduit terminates in a chamber 23 on one side of a diaphragm 24, which forms a part of a signal control system as will be herein-after described.

The construction of the generator shown is set forth and claimed in Patent No. 1,193, 95 124, issued to N. G. Copley on August 1, 1916, but for purposes of identification of this invention, it is sufficient to state that the generator 21 is positioned below the normal water level, but above the bottom of the boiler, so as to insure free passage of water through the connection 14. Under normal conditions then, the generator 21 entirely surrounds that portion of the tube 18 having water therein so that the fluid pressure within the generator is less than the force exerted by the spring 25. In this way the mechanism controlled by such spring is normally inactive.

In the boiler illustrated, the fuel used is 110

in the form of oil or gas and is conveyed to the boiler through the conduit 12. Accordingly I have provided in such conduit a valve 26, which is directly connected to 5 a stem 27, and which is adapted to be actuated by the spring 25. While the boiler is in operation, the valve is maintained in open position, as shown in Fig. 3, wherein the spring is compressed.

10 The mechanism for controlling the alarms, comprises a diaphragm plate 30 carried by a spindle 31 which is slidably mounted in a standard 32; this plate abuts the diaphragm 24 and is held thereagainst by spring 25 so that under normal operating conditions, the force of such spring is greater than the pressure within the chamber 23 on the opposite side of the diaphragm.

15 The means employed for connecting the spindle to the spring may include a yoke 33 which is pivoted at 34 to the spindle 31, and which is provided with an extension piece 35, the outer end of which terminates in a knob 36. The opposite faces of the yoke may 20 then provide pivotal supports, as at 37, and 38, for the links 39 and 40, respectively. The outer ends of the links or arms 39 are pivoted to the standard 32 at 41 while the outer ends of the links 40 are pivotally 25 connected to the spring plate 43, as at 42. The links 39 and 40 thereby form a toggle joint which transmits lateral motion of the spindle 31 to vertical motion of the spindle 27, which latter actuates the alarm signal.

30 35 The spindle 27 extends through the spring 25 and is supported for longitudinal movement in a transverse member 44, which constitutes part of the standard 32. The uppermost end of this spindle may terminate in a bifurcated portion as at 45 to receive a lever 46 which is pivoted at 47 to the standard 32. This lever as shown in Fig. 2 may 40 be so connected through a suitable member 48 to an operating lever 49 of a whistle 50, that a downward movement of the lever 46 actuates such whistle.

45 The lever 46 is moved downwardly whenever the spindle 27 is longitudinally moved a predetermined amount. In other words, 50 when the water level within the boiler is above the generator 21, the pressure in the chamber 23 is not sufficient to overcome the force of the spring 25, and accordingly the plate 30 is held against the diaphragm with the middle points 37 and 38 of the toggle joint, on that side of the center line adjacent the diaphragm.

55 If for any reason the water level within the boiler should drop until it is on a level 60 with the generator 21, then the steam adjacent the generator 21 raises the temperature and hence the pressure therein until the force of the spring 25 is overcome. Thereupon the spindle 31 is moved longitudinally until the middle points 37 and 38 of the toggle joint

are urged toward the center of the spindle 27. A further increase of pressure in the generator moves the points 37 and 38 beyond the center line of the spindle 27, whereupon the force of the spring 25 is expended 70 in throwing the toggle links to the position shown in Fig. 4 and carrying the spindle 27 downwardly, thereby closing the fuel valve 26 and also actuating the alarm, as, for instance, the whistle 50.

75 When the whistle is actuated, an operator at a remote point is immediately apprised of the location wherein trouble is imminent, the generator 21 being so positioned that sufficient time will be allowed to enable the operator to reach the boiler before any actual damage occurs.

80 An additional precautionary measure, however, is to utilize an electric alarm which is also adapted to be actuated by a downward movement of the stem 27. This alarm may comprise an audible or visible or combined signal 60, at a point remote from the boiler, and preferably at a central control station. In this station, an indicator system may be 85 used for apprising one of the exact boiler requiring attention.

90 In Figs. 2 and 3, I have shown an electric signal as having a source of power 61, with leads 62 and 63, which terminate in the contact plates 64 and 65 on the standard 32, and spindle 27 respectively. In Fig. 3 the contact plates are shown in separated position while in Fig. 4 such plates are in engagement.

95 After the operation of the low water signals is initiated, then such signals will continue in operation so long as steam remains in the boiler, or the source of electric supply remains. This condition occurs by reason of the fact that the spring, when once extended, holds the toggle joint in the position shown in Fig. 4. Accordingly, to re-set the alarm, it is necessary to manually force the yoke 33 inwardly against the tension of the spring 25, thus bringing the plate 30 into contact with the diaphragm, and the points 37 and 38 on the other side of the center line, as shown in Fig. 3.

100 105 The generator 21 is shown as surrounding the conduit 18 and as positioned intermediate the generator 15 and the connection 14. This center conduit therefore, serves as a fluid passageway for actuating the feed water control mechanism, and for operating the alarm apparatus. An advantage of such an arrangement is that the generator for the alarm apparatus may be readily installed on boilers equipped with feed water control mechanism, operating on the thermostatic principle, without cutting the boiler for additional connections. However, if desired, each generator may have its boiler connections independent of the other.

110 115 120 125 130 While I have explained my invention as

having a valve which is adapted to shut off the fuel, it is understood that it may also be satisfactorily employed in coal burning furnaces without destroying the effectiveness 5 of the signal system as controlled indirectly by the water level falling below a predetermined amount. In such cases the valve 26, together with the valve body, may be eliminated, and the bottom of the standard 32 10 may be secured to a bracket (not shown) mounted on the boiler wall. The valve, when employed, and either of the signals, whether the valve be employed or not, constitutes an emergency device normally inactive 15 but effective upon low water occurring.

From the foregoing description it will be seen that I have provided a low water alarm apparatus which is positive in its operation, 20 and which is well adapted for use in connection with the operation of boilers that are separated a considerable distance from each other, thus enabling one operator to tend to a number of such installations without 25 endangering the boilers.

Having thus described my invention, I claim:

1. The combination of a fluid fuel intake pipe leading to a boiler, a valve in said pipe 20 a valve actuating rod extending therefrom, a frame mounted on the valve longitudinally embracing the valve actuating rod, alarm means associated with the rod and frame, a spring within the frame fixed at one end 35 to the frame remote from the valve, and at the other end to the middle of the rod tending to normally force the rod into the valve chamber to close the valve, a toggle loosely fixed at one end to the frame opposite the 40 spring and near the valve and at the other end to the rod adjacent the connection of the rod and spring with the three toggle pivot points but slightly out of alignment with the rod, a lever extending transversely of 45 the frame being limited in travel within the frame and adapted to be manually operated exteriorly of the frame and loosely connected to the middle pivot of the toggle at

its mid-point and connected to a second rod at the other end, a diaphragm associated 50 with the second rod supported at the side of the frame, a pressure chamber enclosed on one side by the diaphragm, so that the diaphragm reacts on the second rod thence on the middle toggle pivot throwing the toggle past center allowing the spring to force the first rod into the valve chamber thereby closing the valve and actuating the alarm means.

2. The combination of a fluid fuel line 60 leading to a boiler, a valve in said line, a valve actuating rod extending from the valve chamber, a frame mounted on the valve extending longitudinally of the valve actuating rod and supporting said diaphragm, a plunger associated with the diaphragm extending into the frame adapted to be forced into the frame responsive to pressure exerted on the diaphragm, a toggle pivotally connected to the frame and to 65 the valve actuating rod and extending along the rod, resilient means connected to the frame and rod tending to collapse the toggle and force the rod into the valve chamber, a lever transverse the frame pivotally connected 70 to the plunger and to the middle pivot of the toggle, means associated with the lever adapted to abut the frame and limit the motion thereof, said lever extending without the frame and adapted to be manually 75 operated, the motion of the lever being so limited that the middle pivot of the toggle is but slightly out of alignment when the valve is open and adapted to be forced past center by pressure on the plunger and further forced beyond alignment as the resilient means forces the rod into the valve chamber, and alarm means associated with the rod and frame to be actuated as the rod is forced into the valve chamber and to remain active until the rod is again lifted by operating the above named lever manually.

In testimony whereof, I hereunto affix my signature.

J. M. BARRETT.
